UNITED STATES PATENT OFFICE.

HENRY S. GASKILL, OF HASTINGS, MICHIGAN.

FIREPROOF VAULT.

Application filed May 16, 1925. Serial No. 30,811.

To all whom it may concern:

Be it known that I, HENRY S. GASKILL, a citizen of the United States, residing at Hastings, in the county of Barry and State 5 of Michigan, have invented new and useful Improvements in Fireproof Vaults, of which the following is a specification.

This invention relates to improvements in fire proof safe deposit cellar vaults and contemplates the provision of an elongated casting which is preferably formed of galvanized iron and which may be arranged within the walls at any time, during time of construction.

15 Another object of the invention is to provide an inner-lining of asbestos and provide a closure door which includes inwardly beveled sides and snugly received within the corresponding outer ends of the vault and 20 have its outer sides lie flush with the inner face of the cellar wall.

A further object of the invention is to provide one or more auxiliary doors within the vault which are arranged in spaced relation thereon and form heat resisting spaces 25 between the doors in order that the papers or other valuable articles placed within the vault will be prevented from burning.

With the above and other objects in view, 30 the invention further includes the following novel features and details of construction, to be hereinafter more fully described, illustrated in the accompanying drawing and pointed out in the appended claims.

35 In the drawing:

Figure 1 is a longitudinal section taken through the vault when closed and arranged within the wall.

Figure 2 is a front elevation of the vault 40 door when closed.

Figure 3 is a sectional view taken on line 3—3 of Figure 1.

Figure 4 is a vertical section taken on line 4—4 of Figure 3.

45 Figure 5 is a fragmentary section of the vault and showing the relative arrangement of the doors and hinged mountings and locking means for the outer door.

Referring to the drawing in detail, where- 50 in like characters of reference denote corresponding parts, the reference character 10 indicates a wall which is preferably formed of cement and which is adapted to receive and to be moulded therein during 55 the process, or at any time, of construction an oblong shaped vault 11 which is prefer-

ably formed of galvanized iron or some other rust resisting material, and which has its inner edges terminating short with respect to the inner side or face of the wall 10. These 60 inner ends of the vault 11 register with inwardly beveled portions 12 provided upon the four sides of the vault 11 and which are adapted to snugly receive within these beveled portions 12 the corresponding beveled portions 13 formed upon the rear wall 14 of a hollow door 15 which is preferably filled or stuffed between the front and rear walls thereof with asbestos or the like substance as indicated at 16. It will thus be noted that 65 owing to the beveled inclinations upon the inner side of the cellar wall 10 and upon the ends of the rear wall 14 of the door 15 that the said door 15 when positioned upon the front of the vault 11 will have its outer sides 70 lying in the same plane with the inner side walls or face of the cellar wall 1. This door 15 includes a pair of hinged members 17 which include anchoring means in the form of a headed stud 18 which is preferably 75 moulded within the wall 10 in the process, or at any time, of construction and in so doing the studded bolts 18 will securely hold the hinged member 17 in the relative positions 80 so that the door 15 will be swung readily 85 and easily into place and form the neat fit as mentioned in the foregoing.

This door 15 also includes a hasp 19 which is rigidly secured to the outer side and adapted to be swung over a yoke 19' 90 which has its inner ends moulded within the wall 10 during the process of operation and adapted to receive a padlock 20 or the like within this yoke when inserted within the usual cutout portion provided in the hasp 95 19 whereby the vault is locked. This vault 11 includes a layer of asbestos or other fire proof material 21 upon the sides and end wall. Arranged at spaced intervals along the length and within the vault 11 is one 100 or more auxiliary doors 22 which are hinged to the inner sides of the vault as at 23 and which are formed in the same manner as the door 15, namely, having their inner and outer walls spaced and filled with asbestos or the like and which also include handles 24 arranged upon the outer sides thereof to facilitate their opening when it is desirous to remove or place valuables within the walls 11. It is quite obvious that a locking means 110 as used for the door 15 is not necessary for any one of the auxiliary doors 22 and in

order to provide means for holding the doors 22 in their proper positions for rendering the contents of the vault fire proof, I provide substantially L-shaped cross section 5 brackets 25 which are arranged upon the top wall of the vault 11 and include inclined entrance openings 26 therein, the purpose of which will be presently apparent. Extending through the upper side of one or 10 more of the auxiliary doors 22 are lug members 27 which are tensioned outwardly by spring fingers included within the auxiliary doors and tensioned against the under side of the lugs 27 whereby the latter will be 15 normally forced upwardly and inwardly within the inclined entrance openings 26 provided in the upper sides of the cross section substantially L-shaped brackets 25.

It will thus be noted from the foregoing 20 description and accompanying drawing that this invention provides a very useful, convenient and advantageous receptacle for valuables and which owing to its simplicity of construction and arrangement of parts, 25 may be readily and easily moulded within the cellar walls at any time in constructing the foundations of a house and owing to its snug fitting within the walls of a cellar will form no projections or take up any room 30 within a cellar, save for the hinges, hasp and padlock which would in no way interfere with the storage of furniture or any like articles to be placed against the wall 10 of the cellar, not shown. It is manifest that owing 35 to the spaced relation and construction of the doors 15 and 22 respectively, that the articles contained within the vault 11 will be prevented from burning owing to the arrangement of the asbestos or non-inflammable material arranged within the front 40 and rear walls of the doors and owing to the spaced relation of one or more auxiliary doors 22, a heat resisting space is so provided as will materially check any entrance 45 of heat or the like between these doors and in any way endanger the contents of the vault 11.

The invention is susceptible of various 50 changes in its form, proportions and minor details of construction, and the right is

herein reserved to make such changes as properly fall within the scope of the appended claims.

Having thus described my invention what is claimed is:

1. A vault of the character described having a layer of non-inflammable material arranged upon the inner sides thereof, a hollow door being filled with non-inflammable material and having its inner sides inwardly beveled and snugly fitting the inner ends of the vault and corresponding wall and lying in the same plane therewith, a pair of hinged members having their outer ends rigidly secured to the door and their opposite ends anchored or moulded within the vault wall, locking means included upon the door and wall, a plurality of correspondingly constructed auxiliary doors arranged in spaced relation within and extending longitudinally of the vault for creating a heat resisting space therebetween, and holding means included upon the upper sides of the auxiliary doors for holding the same in their relative positions substantially as set forth. 70

2. A vault adapted to be placed or moulded within a wall or the like during the process or at any time of construction having a layer of non-inflammable material arranged upon the inner sides thereof, the outer edges of the vault falling short of the inner face of the wall and including outwardly beveled portions in the wall and registering the inner edges of the vault, a hollow door hinged to the wall and having its sides beveled and snugly fitting within the corresponding outwardly beveled portions provided in the wall, a plurality of correspondingly constructed auxiliary doors hingedly secured at spaced intervals within the vault, a plurality of cross section substantially L-shaped stops having inclined entrance slots therein, spring tensioned dogs arranged within the top walls of the auxiliary doors and adapted to be readily received within a restricted beveled entrance slot provided in the stop and locking means included upon the outer door and wall in the manner set forth. 85

In testimony whereof I affix my signature.

HENRY S. GASKILL.
